UNITED STATES PATENT OFFICE.

ABRAHAM L. DOW, OF LYONS, COLORADO.

VALVE.

No. 850,740.

Specification of Letters Patent.

Patented April 16, 1907.

Application filed September 20, 1906. Serial No. 335,416.

To all whom it may concern:

Be it known that I, ABRAHAM LINCOLN Dow, a citizen of the United States, and a resident of Lyons, in the county of Boulder and State of Colorado, have invented a new and Improved Valve, of which the following is a full, clear, and exact description.

This invention relates to certain improvements in valves, and especially in hydrant-valves, whereby the valve and valve-seat may be removed from the casing without disconnecting the latter should it become necessary to repair or replace any of the working parts. This is of particular value around hydrant-valves, which are usually so located that it is very difficult to get at the valve to repair it.

Reference is to be had to the accompanying drawing, which illustrates one embodiment of my invention and in which the single figure shown is a central longitudinal section through the same.

The valve-casing 1 is preferably substantially cylindrical in cross-section and is provided with an inwardly-directed flange 2 adjacent its lower end and adapted to engage with an inner tube to separate the casing into two compartments. The lower end of the casing is provided with a fluid-inlet connection 3, while the cylindrical body portion at a point above the inwardly-directed flange 2 is provided with an outlet-pipe connection 4.

The upper end of the casing has a screw-threaded opening into which is inserted the tube 5, which latter is conical at its lower end and adapted to fit against the beveled edge of the flange 2. The tube is provided with a plurality of perforations along its length and between the top of the casing and the flange 2, whereby liquid may freely pass from the interior to the exterior of the tube. The upper end of the tube may be either provided with a hexagonal nut or with upwardly-projecting lugs 7, whereby a suitable wrench may be applied to screw the tube in place and force it tightly against the tapered edge of the flange 2, which constitutes a seat for the conical end of the tube.

The lower end of the tube 5 is cut perfectly even and constitutes a valve-seat 8, against which a plate 9, constituting the valve, is adapted to be forced. The plate 9 is provided with a downwardly-extending collar 10, into which is screw-threaded the lower end of a valve-stem 11, extending throughout the length of the tube. The

valve-stem 11 is screw-threaded through an opening in the outer end of the tube 5 and at its outer end is provided with means whereby it may be rotated to force it into and out of the tube, and thus force the valve toward or away from the valve-seat. The upper end of the valve-stem is provided with a passage 12, extending longitudinally thereof and having the ends terminating at points one of which is above and the other of which is below the closed end of the tube 5 when the valve 9 is forced against its seat. It will thus be noted that the passage 12 is always open when the valve 9 is closed, but as the latter is opened the upper end of the passage 12 is closed by the end of the tube 5 to prevent the escape of fluid through this passage when the main valve 9 is open.

In case anything happens to the valve or valve-seat to prevent a close fit being secured and causing the valve to leak or in case the parts become worn so that it is deemed advisable to replace them the tube 5 may be screwed out of the casing, and as it carries the valve-stem and valve with it it will be seen that all the working parts may be readily disclosed to view and inspected at leisure.

When the tube is in place, no liquid can pass the tapered seat, but can only escape when the valve 9 is opened by the turning of the valve-stem 11. When the valve and valve-stem are removed by the removal of the tube 5, the valve-stem and its support are also removed, and by turning the valve-stem after the tube has been removed the fit of the valve with the valve-seat may be easily adjusted.

The passage 12 permits the escape of fluid from the tube 5 after the valve is closed, thus avoiding danger due to high pressure in the valve-casing.

Having thus described my invention, I claim as new and desire to secure by Letters Patent—

1. In combination, a valve-casing having inlet and outlet ports, one of which is located at the end of the casing and the other of which is located at the side of the casing, an inwardly-directed partition at the end of the casing having the port, the inner surface of the partition being beveled, a tube screw-threaded to the casing at the opposite end thereof and adapted to contact with the beveled surface of said inwardly-directed flange, a valve adapted to close the inner end of the tube, and a valve-stem carrying said

valve and extending outward through the tube at the opposite end thereof and having a passage, the ends of which communicate with the interior of the tube and with the outside thereof when the valve is closed.

2. In combination, a substantially cylindrical valve-casing having an inlet-port and an outlet-port, one of which is located at the end of the casing and the other of which is located at the side of the casing, an inwardly-directed flange adjacent the end of the casing having the inlet-port, the inner edge of said flange being tapered, a perforated tube screw-threaded into the opposite end of the casing and having the inner end thereof conical and adapted to be forced into contact with the tapered edge of the inwardly-directed flange, a valve adapted to close the in-

ner end of the tube, and a valve-stem extending longitudinally of the tube and supporting said valve, the opposite end of the valve-stem extending outward through the outer end of the tube and being provided with means whereby it may be rotated to operate the valve, said valve-stem being provided with a passage, the ends of which normally communicate with the tube and with the outside atmosphere when the valve is closed.

In testimony whereof I have signed my name to this specification in the presence of two subscribing witnesses.

ABRAHAM L. DOW.
